US0D1058973S

(12) **United States Design Patent** (10) **Patent No.:** **US D1,058,973 S**
(45) **Date of Patent:** **** Jan. 21, 2025**

(54) **CLEANING BOWL**

(71) Applicant: **Lin Lin**, Shenzhen (CN)

(72) Inventor: **Lin Lin**, Shenzhen (CN)

(**) Term: **15 Years**

(21) Appl. No.: **29/951,912**

(22) Filed: **Jul. 11, 2024**

(51) LOC (15) Cl. **07-05**

(52) U.S. Cl.

USPC **D32/35**

(58) **Field of Classification Search**

USPC D32/25, 26, 29, 35, 53
CPC B08B 9/42; B08B 11/02; A46B 17/06

See application file for complete search history.

(57) **CLAIM**

The ornamental design for a cleaning bowl as shown and described.

DESCRIPTION

FIG. 1 is a perspective view of a cleaning bowl showing the claimed design;

FIG. 2 is another perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof; and,

FIG. 9 is a partial enlarged view of FIG. 1 thereof.

1 Claim, 9 Drawing Sheets
